UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ATTACHMENT-PLUG.

1,300,812.

Specification of Letters Patent. Patented Apr. 15, 1919.

Application filed March 15, 1915. Serial No. 14,577.

To all whom it may concern:

Be it known that I, REUBEN B. BENJAMIN, a citizen of the United States, residing at Chicago, in the county of Cook and State of Illinois, have invented new and useful Improvements in Attachment-Plugs, of which the following is a full, clear, concise, and exact description, reference being had to the accompanying drawing, forming a part of this specification.

My invention relates to attachment plugs, and more specifically to separable attachment plugs comprising an insertible portion carrying center and shell contacts and a separable portion carrying binding posts and contacts for engagement with the contacts of the insertible portion.

Among the objects of my invention is to provide an attachment plug which shall be simple of construction, efficient in use and easy to assemble.

Further objects of my invention will be apparent from the following specification taken in connection with the appended claims.

In the drawings, in which I have shown two embodiments of my invention—

Figure 1 is a side elevation of a separable attachment plug embodying my invention; Fig. 2 is an axial section on the line 2—2 of Fig. 1, showing the parts connected, showing the manner in which the contacts of the insertible portion are held between the base and button or cap, and the manner in which the base and button are held together, and the connection between the spring contacts on the insertible portion and the center and shell contacts;

Fig. 3 is a section on the line 3—3 of Fig. 2;

Fig. 4 is a plan view of the detachable portion which carries the binding screws;

Fig. 5 is a perspective view of one of the spring contacts carried by the insertible portion;

Fig. 6 is a perspective view of one of the binding plates and contacts carried by the detachable portion;

Fig. 7 is an axial section showing a modified form of plug in which the spring contacts on the insertible portion are shaped and constructed so that they will properly engage either the contacts of a detachable member provided with contacts having curved tips such as shown in Fig. 2 or sub-

stantially straight contact blades or fingers such as shown in Fig. 7;

Fig. 8 is a perspective view of one of the spring contacts carried by the insertible portion of the modification of Fig. 7; and

Fig. 9 is a perspective view of one of the binding plates and contacts secured to the removable portion shown in Fig. 7.

Referring now to the drawings in detail and first to the modification of Figs. 1 to 6 inclusive, the separable attachment plug comprises an insertible portion 10, which is to be screwed into a lamp socket or other outlet, and a detachable portion 11 to which are connected the conductors leading to any translating device. The insertible portion comprises an insulating base 12 for properly supporting the threaded shell contact 13, the spring contacts 14 which are clamped between the base 12 and the insulating button or cap 15, which cap also carries the eyelet or hollow rivet 16 which forms the center contact of the plug. The center contact 16 is electrically connected with one of the spring contacts 14 by means of a stamped sheet metal conducting plate 17. The base 12 and button 15 are secured together by means of a screw 18 which extends through the eyelet 16 into threaded engagement with a nut 19 which is seated, and non-rotatably held, in an axial recess 20 in the base 12. The eyelet 16 extends through an opening 21 in the plate 17 and is flanged over beneath it, as shown at 22, to hold the plate securely on the button 15. The threaded shell 13 has an inwardly extending flange 23 at its upper edge lying between the base 12 and the button 15. A part of this flange 23 extends inwardly farther than the other part, as shown at 24, to form an electrical connection with a bent over portion 25 of one of the spring contacts 14. The plate 17 has a bent over portion 26 which forms an electrical connection with the bent over portion 27 of the other spring contact 14. These spring contacts 14 are located in recesses 28 in the base 12. The base 12 is provided, at its upper end, with a boss 29, the opposite shoulders of which assist in positioning the bent over portions 25 and 27 of the spring contacts 14 to hold the latter in their proper position.

It will be noted that the threaded shell 13 and the bent over portions 25 and 27 are clamped in place between the base 12 and

button 15 and that the clamping of these two parts together by means of the screw 18 brings the portions 24 and 26 to good electrical connection with the bent over portions 25 and 27 of the spring contacts. The button 15 is recessed, as shown at 30 to accommodate the boss 29 and the plate 17. The lower end of the recesses 28 is enlarged as shown at 31 to permit the entry of the contacts on the detachable portion and to permit the necessary movement of the spring contacts 14. The detachable portion 11 has an axial opening 32 for the passage of the conductors to which the translating device is attached, which opening leads to a recess 33 in the upper face of the insertible portion in which the binding plates 34 are seated. The binding plates 34 are secured to the detachable portion 11 by means of screws 35 having a threaded engagement with bushings 36 which are molded in the insulating detachable portion 11. The binding screws 37 to which the conductors for the translating device are secured are threaded into the binding plates 34. The contact tongues or fingers 38 extend upwardly from the binding plates 34 and are provided with curved upper ends 39 for engagement with correspondingly curved portions 40 on the spring contacts 14. The lower ends of the contacts 14 are provided with lugs 41 which are movable in recesses 42 in the base 12, the lugs 41 being provided to guard against the entry of the fingers 38 on the wrong side of the spring contacts 14 and also to guide the fingers 38 properly.

In assembling the insertible portion of the plug the spring contacts 14 are dropped in place in the recesses 28, the threaded shell 13 is slipped over the base 12 and the cap or button 15 carrying the center contact 16 and plate 17 is placed on top of the base 12. The nut 19 is then dropped into the recess 20 and the screw 18 is threaded into the nut 19 to draw the button 15 and the base 12 together to clamp the spring contacts 14 and threaded shell 13 in place and to force the parts 24, 25, 26 and 27 into engagement with each other to insure a good electrical connection. The circuit through the plug is through the center contact 16, plate 17, spring contacts 14, contact finger 38, binding plate 34, through the translating device to the other binding plate 34, through the other contacts 38 and 14, and through the parts 25 and 24 to the threaded shell contact 13.

In the modification of Figs. 7, 8 and 9 the parts are substantially the same as in the modification of Figs. 1 to 6 except that the spring contacts 43 carried by the insertible portion are so shaped and constructed that they will engage either contacts having curved tips which will permit separation of

the detachable portion by movement other than in a straight line or with contacts comprising straight blades in which the detachable portion can only be separated by a straight line movement. These contacts 43 are provided with bent over upper ends 44 for engagement with the conductors 24 and 25 and have a straight portion 45 for engagement with the straight blades 46 which are secured to the detachable portion 11 by means of screws 35 engaging bushings 36 molded in the detachable portion 11, as in the modification of Figs. 1 to 6. The spring contacts 43 are also provided with curved lower ends 47 for engagement with a detachable portion having contacts provided with curved tips 39 such as shown in the modification of Figs. 1 to 6. Lugs 48 are struck up from the straight portion 45 of the contacts 43 for engagement with openings 49 in the straight blades 46 to securely hold the blades 46 when the latter are brought into engagement with the contacts 43. The insertible portion of the plug in the modification of Figs. 7, 8 and 9 is assembled in the same manner as the plug in the modification of Figs. 1 to 6, and the circuit through the plug is the same.

Having thus described my invention what I claim as new and desire to secure by Letters Patent is:—

1. An attachment plug comprising an insulating base, a shell contact supported by said base, an insulating member, a center contact supported by said member, and a contact held between said base and member, said center contact comprising an eyelet, a conductor having an opening through which said eyelet extends, said conductor extending between said base and member into engagement with said contact.

2. A quick detachable electrical connector comprising an insulating base having a recess therein, and a spring contact within said recess having a straight portion for engagement with a straight contact blade and having a curved portion for engagement with the curved contact of a separable portion which may be separated by movement other than in a straight line, in combination with a separable insulating member having a straight contact blade engaging the straight portion of said spring contact.

3. A quick detachable electrical connector comprising an insulating base having a recess therein, and a spring contact secured at one end to said insulating means, and having its other end free, said spring contact having a straight portion adjacent its secured end for engagement with a straight contact blade of a separable portion which is separated by a straight line movement, and having a curved portion adjacent its free end for engagement with a curved contact other than in a straight line, in

combination with a separable insulating member having a straight contact blade engaging the straight portion of said spring contact.

5. A quick detachable electrical connector comprising an insulating base having a recess therein, and a spring contact within said recess having a straight portion for engagement with a straight contact blade, 10 and having a curved portion for engagement with the curved contact of a separable portion which may be separated by movement other than a straight line, said straight portion of said contact having a lug struck 15 up therefrom for engagement with an opening in said straight contact blade.

5. A quick detachable electrical connector comprising an insulating base having a recess therein and a spring contact within 20 said recess having a straight portion for engagement with the straight contact blade of a coöperating connector member, said straight portion being of sufficient extent to form a good electrical and mechanical connection between the two connector devices, 25 said spring contact also having a curved portion for engagement with the curved contact of a separable connector device, whereby said quick detachable connector may be 30 used with coöperating connector devices having either straight or curved contacts.

6. A separable attachment plug comprising an insulating base, a shell contact supported thereby, said base having a pair 35 of passages therethrough substantially parallel to the axis of said base on opposite side of said axis, said base having a shoulder extending from one of said passages toward said axis, a spring contact extending with- 40 in said passage and having a base portion extending toward said axis and engaging said shoulder, an insulating member, a center contact supported by said member, said contact base being clamped between said 45 shoulder and member, an insulating support, a contact blade supported thereby for engagement with said spring contact, said

blade when in engaging position being nearer said axis than said spring contact is.

7. A separable attachment plug comprising 50 an insulating base, a shell contact supported thereby, said base having a pair of passages therethrough substantially parallel to the axis of said base on opposite sides of said axis, said base having a pair of 55 shoulders extending from said passages toward said axis, spring contacts extending within said passages and having base portions extending toward said axis and engaging said shoulders, an insulating member, 60 a center contact supported by said member, said contact base portions being clamped between said shoulders and said member, said shell contact having an integral flange portion also clamped between one of said 65 shoulders and said members for engagement with one of said contact bases, an insulating support, contact blades supported thereby for engagement with said spring contacts, said blades when in engaging position being 70 nearer said axis than said spring contacts are.

8. A quick-detachable electrical connector device comprising contact means, an insulating base recessed to receive said contact 75 means, said contact means including a straight contact portion for engaging the straight contact blade of a coöperating connector member, separable by straight-line movement, of sufficient extent to form a 80 good electrical and mechanical connection between the two connector devices, said contact means including also a curved contact portion for engagement with the curved contact of a separable connector device which 85 is separable by angular movement.

In witness whereof, I have hereunto subscribed my name in the presence of two witnesses.

REUBEN B. BENJAMIN.

C. F. STRANBERG.

It is hereby certified that in Letters Patent No. 1,300,812, granted April 15, 1919, upon the application of Reuben B. Benjamin, of Chicago, Illinois, for an improvement in "Attachment-Plugs," errors appear in the printed specification requiring correction as follows: Page 2, line 126, claim 3, commencing with the word "of," strike out through line 127; same page and claim, line 130, after the word "contact" insert the words *of a separable portion which may be separated by movement*; and that the said Letters Patent should be read with these corrections therein that the same may conform to the record of the case in the Patent Office.

Signed and sealed this 17th day of June, A. D., 1919.
